DECANTER

Ronald A. Kassin, New York, N.Y., assignor to Schenley Industries, Inc., New York, N.Y., a corporation of Delaware

Filed Aug. 18, 1967, Ser. No. 8,317

Term of patent 14 years

Int. Cl. D9—01

U.S. Cl. D9—119

FIG. 1

FIG. 2

FIGURE 1 is a side elevational view of a decanter embodying my new design, the opposite side being identical with the illustrated side;

I claim:

The ornamental design for a decanter, as shown and described.
